UNITED STATES PATENT OFFICE.

HENRY W. STRASSHOEFER, OF CLEVELAND, OHIO.

CARPET-CLEANING MACHINE.

No. 821,764.

Specification of Letters Patent.

Patented May 29, 1906.

Application filed February 11, 1904. Renewed November 1, 1905. Serial No. 285,368.

To all whom it may concern:

Be it known that I, HENRY W. STRASSHOEFER, a citizen of the United States, residing at Cleveland, in the county of Cuyahoga and State of Ohio, have invented a certain new and useful Improvement in Carpet-Cleaning Machines, of which the following is a full, clear, and exact description, reference being had to the accompanying drawings.

10 A quite common way of cleaning and renovating carpets after removing the dust by beating or otherwise is to scrub the surface of the carpet, using brushes and a suitable cleaning fluid.

15 The present invention is a machine adapted especially for scrubbing carpets with cleaning fluid.

It consists in the combination of a movable surface on which the carpet is spread 20 face outward with revolving brushes and means for keeping said brushes charged with cleaning fluid.

It also consists in numerous details of construction and in the more specific combinations of parts, as will be hereinafter set forth more particularly in the claims.

In the drawings, Figure 1 is a sectional elevation of a machine embodying the invention, and Fig. 2 is a front view of the same.

30 A represents a large drum or cylinder of any suitable construction. It should be as light as possible consistently with the necessary strength and rigidity, and it is secured upon a shaft a, which is freely rotatable in 35 suitable bearings in each end member of the frame C, and it may be turned at the desired slow rate by power applied to a sprocket-wheel a², secured to said shaft. Numerous short points a' project out from the surface 40 of the cylinder, and these help to hold the carpet against the movement independent of the cylinder.

B B represent shafts which are parallel with the axis of the cylinder and lie on opposite sides thereof. Secured to these shafts are rollers b, which extend the entire length of the cylinder, as indicated in Fig. 2. Since carpets are of various thickness and since it is desirable to hold the carpets snugly against 50 the cylinder, these rollers should be adjustable, and to that end their shafts are mounted in the lower ends of arms which swing from overhead supports, and springs d are employed to swing said arms so as to yieldingly draw the rollers toward said cylinder.

55 The carpet is additionally held upon the

cylinder by the endless bands or cords or wires F, which pass under the cylinder, over the rollers b, and then down under two sets of grooved rollers h h', secured to rotatable 60 shafts H H'.

E E' E² represent three rotating brushes, the shafts of which are mounted in suitable bearings. Attached to these shafts are sprocket-wheels or pulleys by which they 65 may be driven. These brushes are so placed that they brush against the surface of the carpet on the cylinder. There may be, of course, as few or as many of these brushes as one desires. Associated with said brushes are pans 70 G for containing the cleaning fluid. In each pan is a rotatable corrugated feed-roller I, whose axis is parallel with the axis of the brush and which dips into the contained liquid and contacts with the associated brush. 75 The friction of the brush upon these rollers will generally be sufficient to turn these feed-rollers fast enough; but if not the rollers may be turned by any suitable mechanism. These pans G are provided with hinged 80 covers g, which when open serve as guards to catch and return to the pan that cleaning fluid which is thrown off from the brushes by the action of centrifugal force. The cleaning fluid in these pans may be benzine or 85 gasoline or some other volatile fluid. When the machine is not in use, it is desirable that these pans containing volatile fluid shall be closed to minimize the loss by evaporation. To permit this, the pans are vertically mov- 90 able, this result being attained in the construction shown by attaching said pans to blocks J, which project into vertical grooves in the frame members. The means shown for moving these blocks up or down consist of 95 toggles K, the links of which are pivoted at their ends to said blocks and to fixed pivots below them.

When the toggle is straightened, the associated pan is raised to the desired elevation 100 to permit the contained rollers to coöperate with the brushes. When the toggles are bent, the pans are lowered and the covers may then be closed. The toggles may be bent and straightened by the longitudinal shifting 105 of two bars M, which are connected with the joints of the toggles and which are connected together by a cross-bar M'.

The carpet having been passed into the machine in the manner shown is drawn 110 slowly along in the direction of the arrow by the turning of cylinder A, and it is thoroughly

scrubbed by the action of the brushes and the cleaning fluid with which they are charged. After this has been accomplished and the cleaning fluid has dried out it is desirable to brush up the pile, which will be more or less matted. To accomplish this, the carpet is again run through the machine, by which the brushes, then dry, will brush up the pile. This renovation is assisted by steaming the carpet, and in order that this may be done most efficiently—that is to say, thoroughly and at the proper time—steam-pipes P are arranged below, but close to, the drum, and they have perforations in their tops through which steam-jets are discharged against the carpet.

Having described my invention, I claim—

1. The combination of a rotatable cylinder, rollers on either side thereof over which the carpet may pass, a plurality of endless bands or the like passing over said rollers and under said cylinder, and other guide-rollers under which said bands also pass with a plurality of rotatable brushes located below said cylinder, and means for charging them with cleaning fluid.

2. The combination of a rotatable cylinder, rollers on either side thereof over which the carpet may pass, a plurality of rotatable brushes located below said cylinder, and means for charging them with cleaning fluid.

3. The combination of a rotatable cylinder under which the carpet may pass, rotatable rollers, lying on opposite sides of said cylinder,

der, and over which the carpet may pass, means for yieldingly pressing said rollers toward said cylinder, and a plurality of scrubbing-brushes, which engage with the carpet upon the cylinder and means for operating said brushes.

4. The combination of a rotatable cylinder under which the carpet may pass, rollers on opposite sides of the cylinder over which the carpet may pass, means for holding the carpet between said rollers against the surface of the cylinder, a plurality of rotatable brushes contacting with the surface of said carpet, vertically-movable pans for containing cleaning fluid, feed-rollers in said pans, and means for raising and lowering said pans.

5. The combination of a rotatable cylinder under which the carpet may pass, rollers on opposite sides of the cylinder over which the carpet may pass, means for holding that part of the carpet which is between said rollers against the surface of the cylinder, a plurality of rotatable brushes contacting with the surface of said carpet, vertically-movable pans for containing cleaning fluid, feed-rollers in said pans, and means for raising and lowering said pans, and a cover for each pan hinged thereto.

In testimony whereof I hereunto affix my signature in the presence of two witnesses.

HENRY W. STRASSHOEFER.
